US00D822636S

(12) **United States Design Patent** (10) **Patent No.:** **US D822,636 S**
Liu (45) **Date of Patent:** **** Jul. 10, 2018**

(54) **ACTIVE NOISE CANCELLING WIRELESS EARPHONE**

(71) Applicant: **Zoey Liu**, Guangdong (CN)

(72) Inventor: **Zoey Liu**, Guangdong (CN)

(73) Assignee: **Shenzhen Shangyuan Tech LTD**, Gao
Xin Ji Shu Gong Ye Cun, Nanshan
Dist., Shenzhen, Guangdong (CN)

(**) Term: **15 Years**

(21) Appl. No.: **29/589,656**

(22) Filed: **Jan. 4, 2017**

(51) LOC (11) Cl. **14-01**

(52) U.S. Cl.

USPC **D14/205**

(58) **Field of Classification Search**

USPC D14/205, 223; 181/129, 130, 135;
379/430, 431; 381/380, 381; 455/90.3,
455/575.1, 569.1

CPC H04R 1/10; H04R 1/1066; H04R 25/00;
H04R 25/02; H04R 1/1091

Primary Examiner — Paula Allen Greene

(57) **CLAIM**

The ornamental design for active noise cancelling wireless earphone, as shown and described.

DESCRIPTION

FIG. 1 is a front plan view thereof;

FIG. 2 is a back plan view thereof;

FIG. 3 is a left plan view thereof;

FIG. 4 is a right plan view thereof;

FIG. 5 is a top plan view thereof; and,

FIG. 6 is a bottom plan view thereof.

The broken lines depict environment that forms no part of the claimed design.

1 Claim, 6 Drawing Sheets
